FIG.13

FIGURE 1 is a left side, top and front perspective view of a phonograph spindle adaptor or the like, embodying one form of my new design wherein the front and rear walls near the top are generally vertical;

FIGURE 2 is a top plan view of the adaptor of FIGURE 1;

FIGURE 3 is a bottom plan view of the adaptor of FIGURE 1;

FIGURE 4 is a side elevational view of the adaptor of FIGURE 1;

FIGURE 5 is a front elevational view of the adaptor of FIGURE 1;

FIGURE 6 is a rear elevational view of the adaptor of FIGURE 1;

FIGURE 7 is a left side, top and front perspective view of a phonograph spindle adaptor or the like, embodying another form of my new design wherein the front wall near the top has a slot formed therein and the rear wall near the top has an inclined lip formed thereon;

FIGURE 8 is a rear perspective view of the adaptor of FIGURE 7;

FIGURE 9 is a top plan view of the adaptor of FIGURE 7;

FIGURE 10 is a bottom plan view of the adaptor of FIGURE 7;

FIGURE 11 is a side elevational view of the adaptor of FIGURE 7;

FIGURE 12 is a front elevational view of the adaptor of FIGURE 7; and

FIGURE 13 is a rear elevational view of the adaptor of FIGURE 7.

The fragmentary broken line showings of a phonograph spindle in FIGS. 4 and 11 are for illustrative purposes only.

This application is a continuation of each of my two co-pending applications, Serial No. D. 80,996 and Serial No. D. 80,997, both filed on July 24, 1964, and both abandoned subsequent to filing this application.

I claim:

The ornamental design for a phonograph spindle adaptor or the like, substantially as shown and described.
